UNITED STATES PATENT OFFICE.

JOHN K. STREET, OF WACO, TEXAS.

MEANS FOR VENTILATING GRAIN, &c.

SPECIFICATION forming part of Letters Patent No. 269,135, dated December 12, 1882.

Application filed March 7, 1882. (No model.)

To all whom it may concern:

Be it known that I, JOHN K. STREET, of Waco, in the county of McLennan and State of Texas, have invented certain new and useful Improvements in Means for Ventilating Grain, Vegetables, &c., in Bulk; and I do hereby declare that the following is a full, clear, and exact description of the invention, which will enable others skilled in the art to 5 which it appertains to make and use the same, reference being had to the accompanying drawings, which form a part of this specification.

This invention has for its object to produce a simple, inexpensive, and efficient means of 15 ventilation for wheat-bins, granaries, store-houses, railway freight-cars, holds of vessels, boxes, barrels, and other receptacles where grain, fruits, vegetables, and other perishable articles are temporarily stored or conveyed 20 from one place to another.

In the drawings, Figure 1 is a longitudinal sectional view of a granary or store-house to which my invention has been applied; Fig. 2, a transverse sectional view of the same; Fig. 25 3, a bottom plan view looking from the under side; Fig. 4, a detail view of one of the end caps; and Fig. 5 a modification showing my invention applied to the hull of a vessel.

Referring by letter to the drawings, A designates the structure, which is mounted upon 30 suitable corner-pieces, B, and provided at its top with a ventilator, C.

D denotes longitudinal slots or openings in the bottom or floor of the structure A, which 35 are covered by strips of perforated sheet metal, wire-gauze, or other suitable perforated material, E.

Above the slots D, and at right angles to the same, are arranged transversely one or 40 more series of horizontal perforated tubes, F, the ends of which rest in openings G, formed in the sides H of structure A.

I designates the end caps, consisting of a base-plate, J, having a central opening, K, 45 and semi-cones L. These caps are secured to the sides of the structure by means of their base-plates J at the openings G, with their central openings, K, tallying with the ends of tubes F and the semi-cones L above. It will 50 thus be seen that the latter, while they do not obstruct the free passage of the air, shelter the

openings G from rain, dust, &c., that would damage the grain or other articles inside. Owing to their cone shape the rain-water will readily run off.

It is obvious that the perforated tubes may be arranged longitudinally, diagonally, transversely, or in any other manner without departing from the spirit of my invention.

When my invention is applied to freight-cars, boxes, &c., the application and arrangement of parts is substantially as herein specified; but when applied to the hull of a vessel the slots in the bottom are of course omitted, and the openings G and end caps, I, arranged 60 above water-line in the rail or bulwark of the vessel. The tubes are then curved down through the hold of the vessel and up and out at the other side, and are preferably imperforate until they reach the hold, all as shown 65 in Fig. 5 of the drawings.

In practice the pure air enters at the openings G into the tubes, and from thence escapes through the perforations therein and circulates through the stored matter. It also enters through the slots in the bottom, and the foul air escapes through the ventilator at the top or through the openings by which it entered. A free circulation of pure fresh air is thus obtained, and the fruits, vegetables, grain, &c., prevented from rotting and preserved in 75 a perfectly-fresh state. By this means wheat and other grain is preserved from injury by sweating during the drying process.

Having thus described my invention, I claim 80 and desire to secure by Letters Patent of the United States—

1. The combination, with the tubes, of the protecting end caps, consisting of a base-plate, by which it may be secured to the structure, 90 and provided with a central opening, in which the ends of the tubes are adjusted, and a semi-cone, as set forth.

2. The combination, with the structure provided with transverse ventilating-tubes projecting on the outside of the structure, of the herein-described protecting-caps, consisting of a base-plate provided with a central opening, by which it is adjusted over the projecting ends of the tubes, and with a semi-cone, as set 95 forth.

3. The combination, with the structure hav-

ing parallel longitudinal slots in its bottom extending its entire length, of the transverse perforated tubes arranged at right angles thereto, with their ends projecting through the sides 5 and resting in protecting semi-conical caps, as set forth.

In testimony that I claim the foregoing as my

own I have hereto affixed my signature in presence of two witnesses.

JOHN KENNEDY STREET.
